UNITED STATES PATENT OFFICE.

ANTON J. ROLLERT, OF CHICAGO, ILLINOIS, ASSIGNOR TO THEODORE A. KOCHS, OF SAME PLACE.

DESIGN FOR A MIRROR-CASE.

SPECIFICATION forming part of Design No. 25,928, dated August 11, 1896.

Application filed July 9, 1896. Serial No. 598,611. Term of patent 34 years.

To all whom it may concern:

Be it known that I, ANTON J. ROLLERT, a citizen of the United States, residing at Chicago, in the county of Cook and State of Illinois, have invented a certain new and original Design for Barbers' Mirror-Cases; and I do hereby declare the following to be a full, clear, and exact description of the invention, such as will enable others skilled in the art to which it appertains to make and use the same.

This invention relates to a novel design for a piece of furniture, as hereinafter fully described and claimed.

The accompanying drawing shows a front elevation of my novel design.

My design consists in the novel ornamentation and configuration of a piece of furniture intended for use in a barber-shop, and is known as a "mirror-case." The barber-

chairs are situated in front of these cases.

The design shown in said drawing consists of a back piece divided horizontally a little below its center by lines representing a shelf

1, above which is represented a series of large and small panels 2 and 3, although the end pan-

els are subdivided into two smaller panels 4. Above each of the panels 2 is an ornamented pediment, while above panels 3 and 4 are overhanging pediments, between which and the shelf 1 extend columns, at the top of which are arches having ornamented panels. Below the shelf 1 the back piece is ornamented by panels, while below the panels 3 and 4 forwardly-projecting cabinets are located, having a central upright column extending from the bottom of the mirror-case to the shelf with ornamental brackets between the said columns and shelf. The cabinets are represented half-width at the sides or below panels 4.

I claim as my invention—

The design for a mirror-case, substantially as shown and described.

In testimony whereof I affix my signature in presence of two witnesses.

ANTON J. ROLLERT.
